UNITED STATES PATENT OFFICE.

GEORG FERDINAND BÖGEL, OF ALTONA, GERMANY.

PROCESS OF EXTRACTING TANNING SUBSTANCES.

SPECIFICATION forming part of Letters Patent No. 794,847, dated July 18, 1905.

Application filed February 19, 1902. Serial No. 94,732.

To all whom it may concern:

Be it known that I, GEORG FERDINAND BÖGEL, a subject of the King of Prussia, German Emperor, residing at Altona, Germany, have 5 invented new and useful Improvements in Processes of Extracting Tanning Substances, of which the following is a specification.

This invention relates to a process for the continuous extraction of tanning materials within a battery of centrifugals. To obtain a thorough extraction, even with short batteries, only a part of the substances thrown off from one centrifugal is conveyed to the succeeding centrifugal, while the remainder 15 is returned to the first centrifugal. The comminuted tanning material is introduced into a number of centrifugals placed side by side. Fresh water is supplied to one of the centrifugals, which by the rotation of the latter 20 is driven through the layer of tanning material that accumulates upon its wall, so that the water becomes enriched by the tannin. The thrown-off and accumulated lye is then pumped partly into the next centrifugal and 25 partly back into the first centrifugal, where it is again driven through the layer of tanning material, and so on through the entire series. From the last centrifugal half of the 30 lye passes into the discharge-pipe, while the other half passes back into the last centrifugal. In this way a complete extraction of the tanning material may be obtained without injuriously affecting the same.

In the accompanying drawings, Figure 1 is 35 a plan of an apparatus for carrying my invention into effect; Fig. 2, a section on line G H, Fig. 1; and Fig. 3 an elevation at right angles to Fig. 2.

The letter a' represents the first of a series 40 of centrifugals, which is supposed to be disconnected from the other centrifugals of the battery, so that it may be filled with fresh tanning material. The valve d^2 is opened, and fresh water flows to the centrifugal a^2 . The rotation of the centrifugal a^2 drives this 45 water through the tanning material thrown against the wall of the centrifugal, so as to become saturated therewith. The tossed liquid then accumulates upon the bottom of the 50 fixed vessel which surrounds the centrifugal

and passes through the duct g^2 to the pump f^2 . The pump conveys the liquid through pipe h^2 to union i^2 , from which one half of the liquid is carried by pipe l^2 to centrifugal a^2 , while the other half is carried by pipe k^2 55 to centrifugal a^3 . The liquid returned to the centrifugal a^3 is mixed with the fresh water admitted to the same and is driven through the layer of tanning material in the manner above described, to be again conveyed in equal parts 60 to the centrifugal a^2 and centrifugal a^3 . The somewhat enriched lye carried to centrifugal a^3 is here again driven through the layer of tanning material thrown against the wall of the centrifugal to become further enriched. 65 The lye then accumulates on the bottom of the fixed vessel which surrounds the centrifugal and passes through the duct g^3 to pump f^3 , which conveys it through pipe h^3 to union i^3 . From this union one half of the liquid is 70 returned by pipe l^3 to centrifugal a^3 and the other half is conveyed by pipe k^3 to centrifugal a^4 . Within the centrifugal a^4 the operation is repeated, and the agitated and now finished lye is pumped through pipe l^4 , partly 75 back to centrifugal a^4 and partly through pipe k^4 , to discharge-pipe n' . The extracting operation is repeated in the above manner until the contents of centrifugal a^2 are completely 80 leached, when the valve d^2 is closed and the pipe k^4 is placed over the inlet-funnel of pipe o' , while the pipe k' is placed over the inlet-funnel m' of the discharge-pipe n' and the valve d^3 is opened. The fresh water will now 85 flow to the centrifugal a^3 , is here thrown through the layer of tanning material and collected at the bottom of the centrifugal, to be carried by pump f^3 and pipe h^3 to union i^3 . From this union one half of the liquid passes by pipe l^3 back to centrifugal a^3 , while the 90 other half passes by pipe k^3 to centrifugal a^4 . In centrifugal a^4 the process is repeated and the agitated lye is carried by pump f^4 and pipe h^4 to union i^4 . From this union one half of the liquid is conveyed by pipe k^4 back to centrifugal a^4 , while the other half is conveyed 95 by pipe o' to centrifugal a^4 . After the lye has then been thrown through the layer of tanning material in centrifugal a^4 the now finished lye is conveyed through pump f^4 and 100

conduits $h' i' l'$, one half back to centrifugal a' and the other half through conduits $h' i' k'$ to funnel m' of the discharge-pipe. The extraction thus takes place in the centrifugals 5 a^3 , a^4 , and a' , while the centrifugal a^2 is ready to be filled with fresh tanning material for a period sufficient to permit the complete extraction of the tanning material in the centrifugal a^3 . If this extraction has taken place, 10 the valve d^3 is closed and the pipe k' is placed over the centrifugal a^2 , while the pipe k^2 is placed over the inlet-funnel m^2 of the discharge-pipe n' . The valve d^4 is also opened, so that the extracting process will be carried 15 on in the centrifugals a^4 , a' , and a^2 , while the centrifugal a^3 may be filled with fresh tanning material. In this way the separate centrifugals may be successively filled without

causing any longer interruption in the working than is required for setting the pipes and 20 valves.

What I claim is—

Process for the continuous extraction of tanning material by means of a battery of centrifugals, which consists in conveying part of 25 the lye from one centrifugal to the next centrifugal, and returning the other part of the said lye back to the first centrifugal, substantially as specified.

Signed at Hamburg, Germany, this 5th day 30 of February, A. D. 1902.

GEORG FERDINAND BÖGEL.
